UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

SEWING-MACHINE.

1,139,093.

Specification of Letters Patent. Patented May 11, 1915.

Application filed November 26, 1906. Serial No. 345,201.

To all whom it may concern:

Be it known that I, RUSSEL G. WOODWARD, a citizen of the United States, residing at Waukegan, in the county of Lake, State of Illinois, have invented certain new and useful Improvements in Sewing-Machines, of which the following is a description, reference being had to the accompanying drawing and to the letters and figures of reference marked thereon.

My invention relates to improvements in sewing machines and more particularly to sewing machines in which a trimming mechanism is provided for trimming off the edge of the fabric to be overstitched, prior to the stitching operation.

The object of my invention is to provide a combined edge guide and trimming mechanism which shall be simultaneously adjusted relative to the needle of the stitching mechanism.

A further object of the invention is to provide a combined edge guide, trimmer and strip guide all of which are simultaneously adjusted relative to the needle.

A still further object of my invention is to provide a combined trimmer, edge guide, strip guide, hemmer and uncurler all of which coöperate in preparing the edge of the fabric for the stitching mechanism, and properly locating the same relative thereto.

These and other objects will in part be obvious and will in part be more fully hereinafter described.

My invention consists in the novel parts and arrangements hereinafter described and shown in the accompanying drawings.

In the accompanying drawings, which show one embodiment of my invention:—
Figure 1 is a side elevation of the forward end of a machine having my improvements applied thereto; Fig. 2 is a plan view of a portion of the work support showing the presser foot, edge guide and hemmer and parts of the stitching mechanism, certain parts of the machine being omitted in this view for the sake of clearness; Fig. 3 is a side view showing the presser foot, the trimming blades, and the edge guide, and their relation to the work support and each other; Fig. 4 is a rear detail perspective of the un-

curling member; Fig. 5 is a front detail perspective of the uncurler and the stitch supporting finger; Fig. 6 is a sectional view through the work support and the lower trimmer support showing the manner of adjustably supporting said trimmer; Fig. 7 is a sectional view through the work support showing a rear plan view of the lower trimmer support and the edge guide; Fig. 8 is a detached perspective view of the lower trimmer support, the edge guide and the auxiliary support for said trimming member; Fig. 9 is a rear elevation view of the cover plate for the operating mechanism underneath the work support, also showing the strip guide and the means for yieldingly supporting the same; Fig. 10 is a detached perspective view of the strip guide; Fig. 11 is a detached perspective view of the cover plate for the mechanism underneath the work support; and Fig. 12 shows the manner of folding the fabric as it is presented to my machine.

In the drawings the overhanging arm 1 supports a needle bar 2, which is reciprocated therein by means of a lever 3 through an eccentric strap 4 from the main shaft 4^a beneath the work support. Said lever 3 is connected to the needle bar 2 by means of a link 5. The needle bar carries a needle 6 at its lower end and coöperating with said needle is a spreader 7 and a looper 8 which are of the usual construction and will not require further description.

The presser bar 9 carries a presser foot 10, at its lower end. Said presser foot 10 comprises a shank portion and a pivoted foot portion 11 which is yieldingly held upon the work support 12 by means of a spring 13. This presser foot 10 carries a stitch supporting finger 14, which is secured thereto by a screw 15. Said stitch supporting finger lies adjacent to the path of the needle and the stitches are fed therefrom in the usual manner. I also provide the presser foot 10 with an uncurling member 16 which is secured to the presser foot by means of a screw 17. Said uncurler has a sharp edge which is inclined to the line of feed and so located relative to the work support that the edge of the fabric as it is fed to the

needle is drawn underneath the sharp edge 18 and uncurled so that when the edge reaches the trimming mechanism the same lies smoothly upon the work support.

- 5 The trimming mechanism and strip guide are practically of the same construction as that shown in the application of Lansing Onderdonk, 273,574, filed Aug. 10, 1905. Said trimming mechanism comprises an upper cutting member 19 which is supported by the member 20 and receives its oscillations therefrom. The lower trimming member 21 as shown in detail in Figs. 6, 7, and 8 is carried by a support 22 which is in turn supported by the work support 12. Said work support is slotted as at 23 and a hand screw 24 passing through said slot and engaging the trimming support, serves to hold said support in adjusted positions.
- 10 Passing through the front end of the work support is a shaft 25 which has a thumb piece 25' for turning the same which carries a graduated dial 26. A plate 27 secured to the inner face of the work support 12 engages a groove 28 in the shaft 25. This plate 27 allows the shaft 25 to be rotated but prevents any longitudinal movement of said shaft. The shaft 25 carries on its inner end a threaded portion 29 which engages a threaded recess 30 in the end of the trimmer support.
- 15

The edge guide 31 has a depending shank 32 which is secured to the trimmer support 22 by means of screws 33. Said edge guide 35 31 extends above the work support 12 and has its upper surface inclined downward toward the stitching point. The front end of the edge guide is however, slightly raised above the work support. The lower trimming member is located immediately adjacent the edge guide 31 and extends slightly above the work support and forms a continuance of the edge guide for the fabric as clearly shown in Figs. 3 and 7. In the rear 45 of the stitching point is a guard 34 which is secured to the work support and extends along the path of the edge of the fabric to a point adjacent the stitch supporting finger. Said guard serves to prevent the 50 chain of stitches between garments from being deflected into the trimmer operating mechanism.

The bed plate 35 has a bracket 36 secured thereto and hinged to said bracket 36 is a cover plate 37. Said cover plate extends upwardly and backwardly so as to cover the operating parts of the stitching mechanism underneath the work support and at the same time render the same accessible. Slid- 60 ingly secured to the cover plate is a strip guide 38. The cover plate 37 is provided with a slot 39 and the strip guide is secured to the cover plate by a member 40.

Said member 40 is located on the opposite side of the cover plate from the strip guide 65 38 and is secured thereto by screws which pass through the slot in said plate.

The member 40 has an upwardly turned end against which a spring 41 bears. Said spring 41 is carried by an arm 42 rigidly 70 supported by the cover plate. The strip guide 38 is normally pressed by the spring 41 against the front of the trimmer support 22 and the trimming blade 21. Said strip guide extends up across the line of trimming 75 and is located slightly in the rear of the trimming point so that the strip severed from the fabric by the trimmers is guided away from the stitching mechanism.

It will be noted that inasmuch as the edge 80 guide is mounted upon the support for the lower trimming member and the strip guide is yieldingly held against the trimmer support that when said trimmer support is adjusted relative to the needle that the edge 85 guide and also the strip guide will be simultaneously adjusted therewith. The upper trimming member is spring pressed against the lower member so that said upper member also is adjusted with the lower member. This simultaneous adjustment of the two trimming blades is of the usual construction and therefore, the manner of supporting the upper trimming member has not been shown in detail. 90

The work support 12 is provided with a pivoted section 43 on which is mounted a hemmer 44. Said hemmer has a forwardly extending arm 45 which is bent back upon itself at 46 in order to fold and guide the 100 fabric properly to the stitching mechanism.

In the operation of my machine the fabric is folded as shown in Fig. 12 and as the same passes through the machine the body of the fabric rests on the work support 12, 105 while the hem which is being stitched passes between the arms of the hemmer 44 with its free edge resting upon the ledge 47. The free edge passes down over the edge guide 31 while the folded edge of the fabric passes along side of and is guided by said edge guide. As the free edge of the fabric passes underneath the uncurler 18, the same is uncurled and is so held until the edge reaches the trimming mechanism which operates to 110 trim said raw edge. As soon as the edge which has been trimmed passes the trimming mechanism, it is presented to the stitch forming mechanism which operates to secure the same to the body fabric. The edge 115 guide 31 is shown as inclined downward for the reason that as the fabric passes through the hemmer, the folded portion of the fabric is separated from the body portion, by the member 46 of the hemmer. At the 120 stitching point however, the folds in the 125

fabric are superposed directly upon each other. The edge guide 31 over which the edge of the material to be trimmed passes, is therefore inclined downward so as to lie 5 substantially in the path of movement of the edge of the fabric and to form a support for the same. This is especially desirable as the uncurling device which engages the edge of the fabric operates upon the same 10 between the stitching point and the hemmer, and there must necessarily be a support for the edge in order to render the uncurler operative.

The purpose of the strip guide as above 15 noted, is to engage the strip of material severed from the edge of the body fabric and to deflect it off to one side away from the stitching mechanism.

By my improved arrangement of parts 20 wherein the trimmer and edge guide may be simultaneously adjusted, it will be seen that the edge guide may be properly adjusted relative to the trimmer and thereafter, when it is desired to shift the edge guide relative 25 to the stitching mechanism for varying thicknesses of fabric which would require also an adjustment of the trimmer, the adjustment of these parts may be quickly brought about by a single device and without 30 out in any way disturbing the relative adjustment of the trimmer and the edge guide.

By making the strip guide simultaneously 35 adjustable with the edge guide and trimmer, the operator does not need to make a separate adjustment of this part which must have a definite position relative to the trimmer but by a single thumb nut all of the parts necessary to be adjusted may be quickly shifted so that the machine is rendered capable of operating upon material 40 of any thickness.

It is obvious that minor changes in the details shown and described may be made without departing from the spirit of my invention.

Having thus particularly described my invention, what I claim as new and desire to secure by Letters Patent, is:—

1. A sewing machine including in combination, a stitch forming mechanism, a trimming mechanism including a normally stationary lower blade and a coöperating movable upper blade, an edge guide, and means for positively adjusting the lower blade 50 laterally with respect to the stitch forming mechanism independently of said upper blade, and for simultaneously adjusting said edge guide.

2. A sewing machine including in combination, a stitch forming mechanism, a trimming mechanism including a normally stationary lower blade and a coöperating movable upper blade, an edge guide, a strip

guide and means for positively adjusting the lower blade laterally of said stitch forming mechanism independently of the upper blade and for simultaneously adjusting said edge guide and said strip guide. 65

3. A sewing machine including in combination stitch forming mechanism, trimming 70 mechanism, comprising a trimmer support, a trimmer blade carried thereby, an edge guide carried by said trimmer support, a strip guide, and means for yieldingly pressing said strip guide against the trimmer 75 support and means for adjusting said trimmer support; substantially as described.

4. A sewing machine including in combination a presser foot, stitch forming mechanism, an edge guide, an uncurler carried 80 by said presser foot and coöperating with the upper face of said edge guide to uncurl the fabric, a trimming mechanism comprising a trimmer support, a trimmer blade carried thereby and means for positively 85 and simultaneously adjusting said trimmer blade and edge guide relative to the stitching mechanism; substantially as described.

5. A sewing machine including in combination, a stitch-forming mechanism, a trim- 90 ming mechanism, an edge guide, a strip guide movable relative to the trimming mechanism, and means for simultaneously adjusting said trimming mechanism, edge 95 guide and strip guide relative to the stitch mechanism, said edge guide being located in advance of the trimmer; substantially as described.

6. A sewing machine including in combination, a stitch-forming mechanism, a trim- 100 ming mechanism, an edge guide, a strip guide movable relative to the trimming mechanism, and means for simultaneously adjusting said trimming mechanism, edge 105 guide and strip guide relative to the stitching mechanism, said strip guide being located to one side of said trimmer and edge guide; substantially as described.

7. A sewing machine including in combination, a stitch-forming mechanism, a trim- 110 ming mechanism, an edge guide, a strip guide movable relative to the trimming mechanism, and means for simultaneously adjusting said trimming mechanism, edge 115 guide and strip guide relative to the stitching mechanism, and a pivoted hemming device, whereby the hemmer can be moved out of the path of the strip guide; substantially as described.

8. A sewing machine including in combi- 120 nation a work support, a trimming mechanism comprising a stationary lower blade, a support for said blade mounted beneath the work support, means for adjusting said support, means for holding said support in 125 its adjusted positions, an edge guide carried

4
by said support, said edge guide extending above the work support, a strip guide yieldingly moved toward said trimming mechanism, and means whereby said strip guide 5 is adjusted with said trimmer support.

9. A sewing machine including in combination, a work support, a trimming mechanism, including a lower blade, a support for said lower blade mounted beneath the work 10 support, means for adjusting said trimmer support, a cover plate, a strip guide slid-

ingly connected to said cover plate, means for yieldingly forcing said strip guide against said trimmer support, and an edge guide carried by said trimmer support. 15

In testimony whereof I affix my signature, in presence of two witnesses.

RUSSEL G. WOODWARD.
